ABSTRACT

A receptacle for cigar and cigarette butts, especially adapted to be installed in a public area, comprising a main body supported on an upright stand and comprising a hollow spherical upper portion having a butt inlet opening and a downwardly converging hollow conical portion contiguously communicating with the hollow interior of the spherical portion and having a butt outlet opening normally closed by a door. The bottom surface of the interior of the conical portion is downwardly sloped toward the outlet opening, whereby the butts deposited in the receptacle flow out automatically through the outlet opening when the door is opened.

CIGARETTE BUTT RECEPTACLE

BACKGROUND OF THE INVENTION

This invention relates generally to receptacles for cigar and cigarette butts, and more particularly to a cigarette butt receptacle adapted to be set up along sidewalks or in any public or private area wherein scattered cigar and cigarette butts cause a nuisance.

Heretofore, various types of receptacles for cigar and cigarette butts have been proposed. For instance, in railway stations or public halls where a great many people gather, smoking stands, cans, or bins of comparatively large sizes and of various designs are placed in the area wherein smoking is allowed.

Most of such smoking stands or the like are made of refractory materials such as metals, ceramics, and sometimes stones and frequently include fire extinguishing agents such as water, sand, and the like. The smoking stands and the similar receptacles are further constructed in such a manner that cigar or cigarette butts collected therein can be easily removed therefrom, and that they have a self-indicative feature or features by way of their colour, configuration, or notation, whereby people can easily discriminate the smoking stands from remote points through a glance over the area.

However, these smoking stands and the like used in, for instance, railway stations are, in most cases, too large in size and too complicated in construction, so that they are unsuitable to be set up along sidewalks and at bus stops where the expected amount of the cigar and cigarette butts is not as great.

SUMMARY OF THE INVENTION

In view of the foregoing considerations, the primary object of the present invention is to provide a receptacle for receiving cigar and cigarette butts which is adapted to be installed on streets and in public areas, and which is simple in construction and easily manufactured at low cost.

Another object of the invention is to provide a receptacle to receive cigar and cigarette butts which is completely of refractory nature whereby any possibility of causing fire is eliminated even in the event that the cigar or cigarette butts received in the receptacle burn up in a strong wind.

Still another object of the invention is to provide a receptacle which is of a construction free from sharp edges and projections which might harm human bodies and catch clothes.

Still another object of the invention is to provide a cigarette butts receptacle of a construction whereby the cigar or cigarette butts collected therein can be removed therefrom by a one-touch action.

An additional object of the present invention is to provide a cigarette butt receptacle of a self-indicative configuration which can be identified from remote points by a mere glance.

With all of the above described objects and required features in view, a novel cigarette butt receptacle in accordance with the present invention comprises a stand, a hollow main body supported by said stand, said main body including a hollow spherical upper portion and a downwardly converging hollow conical lower portion integrally connected to said spherical portion and internally communicating with the interior of said spherical portion, means forming in said spherical portion an

inlet opening for receiving cigarette butts and the like to be deposited in said main body, means forming in said conical portion an outlet opening for removing the cigarette butts therethrough from within said main body, a door closing said outlet opening, hinge means on said main body and pivotally supporting the door in a manner swingable around a horizontal hinge axis and allowing the door to be hung under gravity in a vertical attitude, when the door is open, with the lower end of the door spaced apart horizontally from the lower end of said outlet opening, latching means for holding said door in closed position in which the door forms part of the conical wall of said conical portion, and means providing a bottom surface of said conical portion, downwardly sloping toward said outlet opening.

The invention will be more clearly understood from the following detailed description thereof when read in conjunction with the accompanying drawings wherein like parts are designated by like reference numerals.

BRIEF DESCRIPTION OF THE DRAWINGS

In the drawings:

FIGS. 1 and 2 are front and side elevational views, respectively, showing a cigarette butt receptacle constituting a preferred embodiment of the present invention;

FIG. 3 is a sectional view, on an enlarged scale, of a main portion of the cigarette butt receptacle shown in FIGS. 1 and 2, which is taken along the line III—III in FIG. 1;

FIG. 4 is a rear elevational view of the main portion of the cigarette butt receptacle shown in FIG. 3; and,

FIG. 5 is a fragmentary sectional view, on a much enlarged scale, of a part surrounded by a circle V in FIG. 3.

DETAILED DESCRIPTION OF THE INVENTION

Referring first to FIGS. 1 and 2, a cigarette butt receptacle constituting a preferred embodiment of the present invention comprises a structural stand 1, for example, in the form of an upright post, adapted to be erected on the ground, pavement, or floor, and a main body generally designated by reference numeral 2 rigidly mounted on the upper end of the structural stand 1.

The main body 2 may be made of a refractory material such as metal, porcelain, or the like. However, for simplicity of description, it is assumed that the main body of the embodiment is made of a metal.

The main body 2 is formed as a hollow integral mass by casting, for example. The mass includes a spherical portion 2a and a conical portion 2b integrally combined with each other and having an internal space 2c therewithin.

As is best illustrated in FIG. 3, the main body 2 has a front opening 3 provided in the spherical portion 2a, of the main body and directed forward and slightly upward, and a rear opening 4 provided in the conical portion 2b of the main body on the rear side thereof.

A front cover or grate 5 having a plurality of perforations 5a and formed with a suitable pattern thereon, if desired, is fitted in the front opening 3 and secured to the portion of the main body surrounding the front opening 3 by means of screws 5b, for example.

A surface 6 on the bottom of the internal space of the conical portion 2b is curved to be inclined downward

and rearward so that the rearmost end of the surface 6 merges into the lower edge of the rear opening 4.

As best illustrated in FIGS. 3 and 4, a door 7 is provided for the rear opening 4 such that it is vertically swingable around a horizontally extended hinge pin 8a of a hinge 8 provided on the outside surface of the main body 2 at a suitable position above the rear opening 4. Since the hinge 8 is located at a position further to the rear from the vertical central axis of the main body 2 than the rear opening 4 provided through the conical portion 2b which is narrowed downwardly, the door 7 made swingable around the hinge pin 8a is suspended downward from the hinge pin 8a when the door 7 is open and left free, and the rear opening 4 is thereby opened.

As best illustrated in FIG. 5, a locking or latching device is provided for the door 7 at the lower end thereof. The device comprises a locking pin 11 passing through a holding part 9 formed integrally with the door 7, and a socket 10 integral with the conical portion 2b of the main body 2. The socket 10 has a hole 10a in axial alignment with the locking pin 11 slidably received in the part 9. When the lower end of the locking pin 11 is received in the hole 10a of the socket 10, the door 7 is locked in the closed state.

The locking pin 11 is provided with a reduced-diameter portion 11a at the upper part thereof so that a shoulder is formed at 11b. Likewise, a hole provided through the holding part 9 is provided with a reduced-diameter portion 9b forming a step 9c at the lower end of the reduced-diameter portion 9b. The relative positions of the step 9c in the hole 9a and the shoulder 11b on the locking pin 11 are so selected that the shoulder abuts the step when the lower end of the locking pin 11 is completely disengaged from the hole 10a of the socket 10.

Since the upper end of the locking pin 11 is initially inserted through the lower end of the hole 9a within the holding part 9 and then a knob 11c is secured to the upper end of the locking pin 11, locking and unlocking operations of the locking device can be effected by the knob 11c, and any possibility of the locking pin 11 dropping out of the holding piece 9 can be completely eliminated.

In use, the cigarette butt receptacle according to this invention is installed on a street, for example, in the upright condition as shown. When cigar or cigarette butts are put into the receptacle through the perforations 5a of the grate 5, the butts drop onto and are deposited on the sloped bottom surface 6 of the conical portion 2b. Since the door 7 is closed, the deposited butts are prevented from flowing outward through the outlet opening 4 and stored on the surface 6 in contact with the inner surface of the door 7.

When the receptacle becomes full of butts, the knob 11c is manually pulled upward until the shoulder 11b abuts the step 9c, whereby the lower part of the locking pin 11 is disengaged from the hole 10a of the socket 10 and the door 7 is allowed to be swung outward under gravitational force into the vertical position wherein the bottom edge of the door 7 is horizontally spaced apart from the bottom edge of the outlet opening 4. It will be understood that with the door taking its vertical position, all of the butts deposited on the bottom sur-

face 6 are allowed to flow outward because of the downward slope of the surface 6. Thus, the removal of the butts from within the receptacle is greatly facilitated.

5 After the butts have been removed, the door 7 is again closed by pulling the knob 11c upward and pressing the door 7 inward. After the door 7 has taken the closed position the knob 11c is released, whereby the locking pin 11 moves downward into the hole 10a of the socket 10 and the door is locked in the closed position.

15 The cigarette butt receptacle according to this invention has a main body with spherical configuration. This is very advantageous since the receptacle is free of any sharp edges and projections which may be dangerous when the receptacle is installed on a street or in public area. Furthermore, the spherical configuration of the receptacle is advantageous because it enables persons to recognize it at a glance. Further, the slightly upward 20 orientation of the inlet opening 3 makes it easy to put cigarette butts into the receptacle.

What is claimed is:

1. In a cigarette butt receptacle comprising a stand, a main body supported by said stand and including a 25 hollow spherical upper portion and a hollow lower portion integrally connected to said upper portion and internally communicating with the interior of said upper portion, means forming in said upper portion an inlet opening for receiving cigarette butts and the like to be 30 retained in said main body, means forming in said lower portion an outlet opening for removing the cigarette butts therethrough from within said main body, and a door normally closing said outlet opening:

the improvement wherein said lower portion comprises a downwardly converging conical body with a wall inclining inwardly in the downward direction, hinge means pivotally supporting said door around a horizontal hinge axis along the upper edge of said outlet opening and in a suspended manner allowing the door to be hung under gravity in a vertical attitude, when the door is opened, with the lower end of the door spaced apart horizontally from the lower edge of said outlet opening, latching means for holding said door in closed position in which the door forms part of the conical wall of said lower portion and means forming a bottom surface of said lower portion, downwardly sloping toward the lower edge of said outlet opening.

2. A cigarette butt receptacle as claimed in claim 1 50 wherein said inlet opening is formed in a front side of said receptacle and said outlet opening is formed in a rear side of the receptacle.

3. A cigarette butt receptacle as claimed in claim 1 wherein said inlet opening is fitted therein with a grating.

4. A cigarette butt receptacle as claimed in claim 1 wherein said inlet opening is directed slightly upward.

5. A cigarette butt receptacle as claimed in claim 1 60 wherein said latching means comprises a holding part secured to the door, a locking pin slidably received in said holding piece, and a socket on said main body, having a hole disposed to receive said locking pin.
